ALLEN E. OSTRANDER, OF RIDGEWOOD, NEW JERSEY, ASSIGNOR TO AMERICAN CAR AND FOUNDRY COMPANY, OF ST. LOUIS, MISSOURI, A CORPORATION OF NEW JERSEY.

CARLINE.

1,097,929.

Specification of Letters Patent.

Patented May 26, 1914.

Application filed June 29, 1911. Serial No. 636,127.

To all whom it may concern:

Be it known that I, ALLEN E. OSTRANDER, residing at Ridgewood, Bergen county, New Jersey, and being a citizen of the United States, have invented certain new and useful Improvements in Carlines, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is a transverse sectional view through the roof of a car showing the improved carline in position. Fig. 2 is plan view of the carline. Fig. 3 is an end view thereof. Fig. 4 is an enlarged fragmentary side elevational view of the same. Fig. 5 is a transverse sectional view, the section being taken on a line of 5—5 Fig. 2.

The object of the invention is to provide a simple strong carline of pressed metal, which is adapted to be connected with the side plates of a car by hangers, which are connected with the principal member of the carline, the principal member being formed of a single piece of pressed metal adapted to extend from side plate to side plate of the car, while the supplemental hanger pieces are brazed, or welded in position and are adapted to pass over the car side plates and down on the outer sides thereof, so as to receive through bolts, which extend through the downwardly extending flanges of the principal member and through downward extensions or flanges of the supplemental hanger pieces.

In car construction, it is preferable where relatively channel shaped carlines are employed that the open sides of the channels shall be at the top with the webs thereof at the bottom. Heretofore it has been impracticable to shape a carline from a single sheet of metal so that the carline could extend over the car side plates and be secured to said side plates and the roof of the car be secured in desired position without cutting the side plates. To avoid this difficulty and to develop the full strength of the metal of the

carline, is one of the objects of the present invention.

Referring to the parts; "F" indicates the side plates; "H" the roof generally speaking; "G" the ridge; "I" the purlins and "B" the body of the carline which is provided at each end with integral downwardly and outwardly extending flanges B' and has connected with its end portions the hanger plates S.

As will be noted in the sectional view Fig. 5 the body of the carline is of channel shape with web portion 1 vertical flanges 2 and supplemental horizontal flanges 3, the open side of the channel being at the top. Connected with the flanges 3 as best shown in Fig. 4 are the end hanger plates S, which may be secured to the flanges 3 by rivets if desired, though I prefer to electrically weld these hanger pieces S as the welding can be done while the parts are held in position with the end flanges B' and 4 at any predetermined distance apart so as to accommodate any required thickness of side plate. An added feature of advantage in having the hanger plates S formed separately is that said plates may be shaped as desired to fit any contour of side plate, say—for example—if Z shapes should be substituted for the side plates "F" shown in the drawing. As shown in the drawing, the body portion "B" of the carline is formed of a single piece of sheet metal bent into shape with the integral top flanges 3 formed thereon extending from end to end and said top flanges are continued downwardly and outwardly at B' as best shown in Fig. 4, the said flanges extending laterally from the vertical flanges 2 sufficiently far to take the securing bolts 5 which pass through the legs 4 of the hanger plates S and through said flange B' as well as the side plates of the car. It will be noted that the flanges 3 are perforated for the reception of the bolt 6 which secures the roof members to the carline.

Having described the invention, what I claim is:—

In a carline, a pressed metal channel member formed from a single sheet and of greater depth at its middle portion than at its ends, said middle and end portions being horizontally disposed and having parallel upper and lower edges, and said channel having integral laterally and vertically extending flanges adapted, respectively, for

connection to car roof longitudinal members and side plates of a car, and supplemental angular extensions secured to said lateral flanges, extending beyond the vertical flanges and adapted to overlap said side plates and extend downwardly on the outer sides thereof.

In witness whereof I have hereunto set my hand in the presence of two witnesses.

ALLEN E. OSTRANDER.

Witnesses:

FREDERICK H. GIBBS,
H. N. HENNESSY.
